[57] CLAIM

The ornamental design for an electrical service, entrance fitting system, as shown and described.

DESCRIPTION

FIG. 1 is a perspective view of an electrical service, entrance fitting system showing my new design. The broken line showing is included for the purpose of illustrating environmental elements only and forms no part of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view thereof being a mirror image; and, FIG. 7 is a perspective view of an electrical service, entrance fitting system showing a second embodiment of my new design. Plan and elevational views are the same as the first embodiment except for the presence of the center fitting.

The side of the electrical service fitting opposite that shown in FIG. 6 is a mirror image thereof and thus is not shown in the drawings.

An electrical meter is shown in phantom in the figures and does not constitute part of my new design.

Fig.7
